HENRY WEICKEL, OF MILWAUKEE, WISCONSIN, ASSIGNOR TO PAWLING AND HARNISCHFEGER COMPANY, OF WEST MILWAUKEE, WISCONSIN, A CORPORATION OF WISCONSIN.

SWITCH AND SAFETY-STOP FOR ELEVATED CONVEYER-TRACKS.

1,139,611.

Specification of Letters Patent. Patented May 18, 1915.

Application filed July 17, 1913. Serial No. 779,441.

To all whom it may concern:

Be it known that I, HENRY WEICKEL, a citizen of the United States, residing at Milwaukee, in the county of Milwaukee and State of Wisconsin, have invented certain new and useful Improvements in Switches and Safety-Stops for Elevated Conveyer-Tracks, of which the following is a specification, reference being had to the accompanying drawing, forming a part thereof.

This invention relates more particularly to elevated monorail track switches and safety stops for conveying apparatus. Its main objects are to facilitate directing the conveying apparatus from one track to another; to prevent the apparatus from accidentally running off the open end of a track at a switch; and generally to improve the construction and operation of devices of this class.

It consists in the construction, arrangement and combination of parts as herein-after particularly described and pointed out in the appended claims.

In the accompanying drawing like characters designate the same parts in the several figures.

Figure 1 is a plan view of a switch and stops embodying the invention; Fig. 2 is a longitudinal section thereof on the line 2-2, Fig. 1; Fig. 3 is an enlarged cross section on the line 3-3, Figs. 1 and 4; and Fig. 4 is an enlarged plan view of a portion of the switch and of the safety stops adjacent to the movable end of the switch tongue, certain parts being broken away and shown in horizontal section.

The switch comprises a main track section *a*, and two or more branch track sections *b* and *c*, suspended from cross pieces at the opposite ends of an elevated frame *d*, preferably made of structural steel, and supported as shown in Fig. 2, by posts *e*. The rails are preferably of I-section on the lower flanges of which the trolley wheels of a conveyer are adapted to run on opposite sides of the web, as indicated by the dotted circle at the left on Fig. 2.

A switch tongue *f*, of I-section, corresponding with that of the main and branch tracks *a*, *b* and *c*, is pivoted at one end to the main track *a* by pivot blocks *g* and *h*,

bolted to the upper flanges of the rails and connected by a pivot pin *i* above the rails, as shown in Figs. 1 and 2. At its opposite end, which is adapted to be turned horizontally into register with the branch track rails *b* and *c*, the switch tongue is provided with a carriage or cross head *j*, bolted to the top flange of the tongue.

A curved cross rail *k* is mounted on and fastened to the tops of the branch track rails *b* and *c* concentric with the pivot pin *i* of the switch tongue, and the carriage or cross head *j* is provided on opposite sides and equidistant from the switch tongue with rollers *l*, the axes of which are arranged lengthwise of the tongue or radial to its pivot pin *i*, and which bear on the rail *k*, thereby firmly supporting the movable end of the tongue and enabling it to be easily shifted from one position to the other.

A horizontally swinging arm *m*, vertically journaled in a bearing on one side of the frame, is connected by a link *n* with an upwardly projecting post or stud *o*, on the cross head *j*, and is provided with a pinion *p* concentric with its journal.

A segment gear *q* of greater radius than the pinion *p* with which it meshes, is vertically journaled in a bearing on the frame *d*, and is provided with arms *r*, projecting therefrom in diametrically opposite directions.

Cables *s*, attached to the arms *r*, lead therefrom over guiding sheaves *t*, which are swiveled on stands *u*, mounted on a cross bar *v* fastened to the top of the track rail at one or more of the approaches to the switch. In the present case the switch shifting connections are shown as leading to the approach along the main track, but they may lead to the approach along either or both branch tracks, any or all of the approaches being provided with such connections. The operating cables, which may consist of wire rope, chains, or partly of ropes or chains and rods, are preferably provided at the ends opposite the arms *r*, as shown in Fig. 2, with handles *w*, within convenient reach of an operator in the cage of a conveyer approaching the switch.

Adjustable stops, consisting of bolts *x*,

secured by nuts *y* in a cross bar *z* on the frame *d* in the path of the arm *m*, are adapted to arrest the movable end of the switch tongue *f* in exact register with the 5 branch track rails *b* and *c*. These stops are located somewhat more than 180 degrees apart in the path of the arm *m*, so as to permit the arm to be turned through an arc of somewhat more than 180 degrees in shifting the switch tongue from one limit of its movement to the other, for a purpose hereinafter explained.

Outwardly yielding buffers are mounted on the cross rail *k* adjacent to the ends 15 thereof in position to engage with a central lug *2* on the carriage or cross head *j* as the switch tongue approaches the limits of its movement in opposite directions. These buffers may each consist of a bolt *3*, mounted and movable lengthwise in a bearing *4* attached to the rail *k* parallel therewith, a spiral spring *5* interposed between said bearing and the head on the inner end of the bolt, and nuts *6* securing the bolt in the 25 bearing and limiting its inward movement. The reaction of these spring buffers on the switch tongue after the arm *m* passes its dead center in either direction, operates to hold said arm in engagement with the stop 30 *x* against which it is carried in shifting the switch tongue, and thus securely retains said tongue in register with either branch track rail into line with which it is brought. The reaction of the buffer springs 35 when the arm *m* is moved away from either stop *x* and passes its dead center, also aids the operator to shift the switch.

To prevent a conveyer from running off from the open end of either branch track, 40 the switch tongue is provided on opposite sides thereof with safety stops *7*, each of which is adapted to block one of the branch tracks when the tongue is shifted into register with the other branch track. These 45 stops are made to pass through openings *8* formed in the webs of the branch track rails *b* and *c*, and to project on opposite sides thereof, as shown in Figs. 1 and 4, so as to engage with the trolley wheels of a conveyer on opposite sides of the rail and evenly distribute the impact of a conveyer 50 running toward the switch to the web of the branch rail against which the stop is adapted to be seated at the end of the opening toward the switch tongue.

To compensate for inaccuracy and variations in fitting and adjustment incident to structures of this kind, and to insure the seating of the stops when they are subjected 60 to the impact of the trolley wheels of a conveyer against the webs of the branch rails at the inner ends of the openings *8*, and to permit the stops to freely pass into position in said openings, the openings are made as shown, larger than the stops, and the stops

are movably mounted on the carriage or cross head *j* and adapted to yield toward the pivoted end of the switch tongue. For this purpose each stop is formed or provided with a squared and shouldered shank 70 or stem *9*, fitted to slide lengthwise in bearings *10* formed on downwardly and oppositely projecting forked arms of the carriage or cross head *j* and disposed radially relative to the pivot *i* of the switch tongue 75 or substantially parallel with the switch tongue.

Spiral springs *11*, surrounding the reduced ends of the stop shanks or stems between the shoulders thereon and the inner bearings *10*, tend to thrust the stops outwardly toward the branch track rails, their movement in that direction being adjustably limited by nuts *12* threaded on the inner ends of the shanks or stems and normally engaging the adjacent bearings *10*. By means of these nuts the stops may be adjusted to pass freely into and through the openings *8* in the webs of the branch track rails, while the springs *11* permit them to yield inwardly against the webs of the rails at the inner ends of said openings, so that the impact of a conveyer running against a stop will be transmitted directly to the rail which is blocked by the stop, and the switch tongue and its connections with the stops will be relieved from injurious shocks and strains.

In the operation of the switch and stops, when the switch tongue *f* and stops *7* are set as shown in Figs. 1 and 2, a conveyer will be directed from the main track *a* to the branch track *b* or vice versa. If a conveyer approaching the switch on the branch track *c* should not be stopped by the operator before it reaches the open end of said track, it would be arrested and prevented from running off the track by the stop *7*, which in this position of the switch tongue blocks said branch track *c*. If a conveyer approaching the switch on the main track *a*, is to be diverted upon the branch track *c*, the operator passing the approach to the switch on the main track, pulls on the left hand cable *s*, thereby shifting the switch tongue *f* from the position in which it is shown in Fig. 1, to the position in which it is shown in Fig. 4, in register with said branch track *c*. By this operation the left hand stop *7* is carried away from and clears the branch track *c*, while the right hand stop *7* is carried into the opening *8* of and blocks the branch track *b*.

As hereinbefore mentioned, connections may be provided for shifting the switch tongue from any or all of the approaches thereto along the main and branch tracks.

Various modifications in minor details of construction and arrangement of parts may be made without materially affecting the 130

operation of the apparatus and without departing from the principle and scope of the invention as defined in the following claims.

I claim:

5. The combination with an elevated frame, main and branch tracks suspended therefrom and a switch tongue pivoted to the main track and adapted to be turned into register with either branch track, of a swinging arm connected by a link with the switch tongue and provided with a pinion, a gear of larger radius meshing with the pinion, and operating connections attached to the gear on opposite sides of its center and leading to an approach to the switch. 70
10. The combination with an elevated frame, main and branch tracks suspended therefrom and a switch tongue pivoted to the main track and adapted to be turned into register with either branch track, of a cross rail mounted on the branch tracks and supporting the movable end of the switch tongue, a vertically journaled swinging arm connected by a link with the switch tongue, and operating connections with said arm leading to an approach to the switch. 75
15. The combination with an elevated frame, main and branch tracks suspended therefrom and a switch tongue pivoted to the main track and adapted to be turned into register with either branch track, of a cross rail mounted on the branch tracks, a roller mounted on the movable end of the switch tongue and bearing on the cross rail, a vertically journaled swinging arm connected by a link with the switch tongue, operating connections with said arm leading to an approach to the switch, and stops co-operating with said arm to limit the movement of the switch tongue in opposite directions in register with the branch tracks. 80
20. The combination with an elevated frame, main and branch tracks suspended therefrom and a switch tongue pivoted to the main track and adapted to be turned into register with either branch track, of a cross rail mounted on the branch tracks, a roller mounted on the movable end of the switch tongue, a vertically journaled swinging arm connected by a link with the switch tongue, and operating connections with said arm leading to an approach to the switch. 85
25. The combination with an elevated frame, main and branch tracks suspended therefrom and a switch tongue pivoted to the main track and adapted to be turned into register with either branch track, of a cross rail mounted on the branch tracks, a roller mounted on the movable end of the switch tongue and bearing on the cross rail, a vertically journaled swinging arm connected by a link with the switch tongue, operating connections with said arm leading to an approach to the switch, and stops co-operating with said arm to limit the movement of the switch tongue in opposite directions in register with the branch tracks. 90
30. The combination with an elevated frame, main and branch tracks suspended therefrom and a switch tongue pivoted to the main track and adapted to be turned into register with either branch track, of a cross rail mounted on the branch tracks, a roller mounted on the movable end of the switch tongue and bearing on the cross rail, a vertically journaled swinging arm connected by a link with the switch tongue, operating connections with said arm leading to an approach to the switch, and stops co-operating with said arm to limit the movement of the switch tongue in opposite directions in register with the branch tracks. 95
35. The combination with an elevated frame, main and branch tracks suspended therefrom and a switch tongue pivoted to the main track and adapted to be turned into register with either branch track, of a cross rail mounted on the branch tracks, a roller mounted on the movable end of the switch tongue and bearing on the cross rail, a vertically journaled swinging arm connected by a link with the switch tongue, operating connections with said arm leading to an approach to the switch, and stops co-operating with said arm to limit the movement of the switch tongue in opposite directions in register with the branch tracks. 100
40. The combination with an elevated frame, main and branch tracks suspended therefrom and a switch tongue pivoted to the main track and adapted to be turned into register with either branch track, of a cross rail mounted on the branch tracks, a roller mounted on the movable end of the switch tongue and bearing on the cross rail, a vertically journaled swinging arm connected by a link with the switch tongue, operating connections with said arm leading to an approach to the switch, and stops co-operating with said arm to limit the movement of the switch tongue in opposite directions in register with the branch tracks. 105
45. The combination with an elevated frame, main and branch tracks suspended therefrom and a switch tongue pivoted to the main track and adapted to be turned horizontally at the other end into register with either branch track, of a vertically journaled swinging arm connected by a link with the switch tongue, stops for limiting the movement of said arm and arresting the switch tongue in register with either branch track, and means for shifting the switch tongue. 110
50. The combination with an elevated frame, main and branch tracks suspended therefrom and a switch tongue pivoted to the main track and adapted to be turned horizontally at the other end into register with either branch track, of a cross rail mounted on the branch tracks and supporting the movable end of the switch tongue, a vertically journaled swinging arm connected by a link with the switch tongue, stops for limiting the movement of said arm and arresting the switch tongue in register with either branch track, and means for shifting the switch tongue. 115
55. The combination with an elevated frame, main and branch tracks suspended therefrom and a switch tongue pivoted to the main track and adapted to be turned horizontally at the other end into register with either branch track, of a cross rail mounted on the branch tracks and supporting the movable end of the switch tongue, a vertically journaled swinging arm connected by a link with the switch tongue, stops for limiting the movement of said arm and arresting the switch tongue in register with either branch track, and means for shifting the switch tongue. 120
60. The combination with an elevated frame, main and branch tracks suspended therefrom and a switch tongue pivoted to the main track and adapted to be turned horizontally at the other end into register with either branch track, of a cross rail mounted on the branch tracks and supporting the movable end of the switch tongue, a vertically journaled swinging arm connected by a link with the switch tongue and provided with a pinion, a gear of larger radius than the pinion meshing therewith and operating cables attached to the gear on opposite sides of its center and leading over guides adjacent to an approach to the switch. 125
65. The combination with an elevated frame, main and branch tracks suspended therefrom and a switch tongue pivoted to the main track and adapted to be turned horizontally at the other end into register with either branch track, of a cross rail mounted on the branch tracks and supporting the movable end of the switch tongue, a vertically journaled swinging arm connected by a link with the switch tongue and provided with a pinion, a gear of larger radius than the pinion meshing therewith and operating cables attached to the gear on opposite sides of its center and leading over guides adjacent to an approach to the switch. 130

connections with said arm leading to an approach to the switch for shifting the switch tongue.

10. The combination with elevated main and branch tracks and a switch tongue pivoted to the main track and adapted to be turned horizontally into register with either branch track, of a cross rail mounted on the branch track, a roller mounted on the movable end of the switch tongue and bearing on said cross rail, a vertically journaled arm and link connection between the movable end of the switch tongue and a stationary part to one side thereof, adjustable stops arranged somewhat more than 180 degrees apart in the path of said arm to arrest the switch tongue in register with either branch track, outwardly yielding spring buffers mounted on the cross rail in the path of the switch tongue and adapted by reaction on the switch tongue to hold said arm in engagement with either stop, and means for shifting the switch tongue from one position to the other.

25. 11. The combination with main and branch tracks and a switch tongue pivoted to the main track and adapted to be turned into register with either branch track, the branch tracks having seats adjacent to their ends next to the switch tongue, of longitudinally yielding stops connected with the movable end of the switch tongue on opposite sides thereof and adapted to block either

branch track when the switch tongue is turned into register with the other branch track, either stop when in blocking position being movable toward the switch tongue into engagement with the seat therefor on the open branch track.

35 12. The combination with elevated single-rail main and branch tracks and a switch tongue pivoted to the main track and adapted to be turned into register with either of the branch tracks which have transverse openings therethrough adjacent to their ends next to the switch tongue, which is provided on opposite sides of its movable end with stop bearings, of stops guided and movable lengthwise of the switch tongue in said bearings and each adapted to pass 40 through the opening in and to block one of the branch tracks when the switch tongue is turned into register with the other branch track, and springs tending to thrust the stops toward the branch tracks and permitting them when subjected to the impact of a conveyer running toward the switch tongue to yield toward said tongue and to be seated against said branch tracks.

45 50 55 In witness whereof I hereto affix my signature in presence of two witnesses.

60 HENRY WEICKEL.
